UNITED STATES PATENT OFFICE.

LEROY BAUMGARTL, OF CHICAGO, ILLINOIS.

DEMOUNTABLE WHEEL.

Specification of Letters Patent. Patented Sept. 21, 1920.

1,353,511.

Application filed March 27, 1917. Serial No. 157,781.

To all whom it may concern:

Be it known that I, LEROY BAUMGARTL, a citizen of the United States, residing at Chicago, in the county of Cook and State of Illinois, have invented a new and useful Improvement in Demountable Wheels, of which the following is a specification:

My invention relates, more particularly, to wheels involving an inner hub-member 10 adapted to be driven, in the case of a drive-wheel, in which case, it would be connected with a drive-mechanism, or mounted in bearings to rotate freely when it is not a drive-wheel; an outer hub-member adapted 15 to telescope with the inner hub-member and to which the spokes of the wheel are connected; and means for releasably holding the outer hub-member in such relation to the inner hub-member that these two members will operate as a unit.

My primary object is to provide a novel and simple construction of wheel of the character above referred to, which will permit the outer hub-member and the parts carried thereby to be easily and quickly assembled with, and removed from, the inner hub-member and which will be strong in construction and positive in operation.

Referring to the accompanying drawings, Figure 1 is a view in longitudinal sectional elevation of the hub-portion of a wheel constructed in accordance with my invention, the hub-members being shown in assembled relation; Fig. 2 is a broken section taken at the line 2 on Fig. 3 and viewed in the direction of the arrow; Fig. 3 is a section taken at the irregular line 3 on Fig. 1 and viewed in the direction of the arrow, showing the clips in elevation; Fig. 4 is a broken sectional view taken through the flanges of the inner and outer hub-members and showing means for initially separating the hub-members in the disassembling operation; Fig. 5 is a face view of a cam-equipped ring forming a part of the locking mechanism for the wheel; Fig. 6 is a broken section taken at the line 6 on Fig. 4 and viewed in the direction of the arrow, this view showing a detail of the means for rotatably adjusting the cam-ring; and Fig. 7, a view in elevation of the pinion-equipped shaft, through the medium of which the cam-ring is actuated.

The inner hub-member of the wheel is represented at 6, it being understood that this hub-member may be of any internal form desired to adapt it to serve as a hub of

a drive-wheel or a driven wheel of a vehicle, this part of the wheel structure in practice remaining attached to the vehicle, namely to the driving-axle of the vehicle 60 when the wheel is a drive-wheel and journaled on a stationary axle when the wheel is not one of the drive-wheels of the vehicle. The outer hub-member of the wheel is represented at 7, this hub-member in practice 65 being connected with spokes (not shown), to the outer extremities of which the felly (not shown) would be attached, whereby this outer hub-member, the spokes and felly referred to would thus be connected together 70 and the whole adapted to be bodily removed from, and assembled with, the inner hub-member 6, as desired, the outer hub-member 7 being hollow and adapted to telescope with the inner hub-member.

In the particular embodiment illustrated, the outer end of the inner hub-member 6 is of frusto-conical form, providing the tapered, or wedge, surface 8, and its inner end carries an annular flange represented at 9. 80 The internal form of the hub-member 7 is such that it will snugly fit the tapered portion 8 of the hub-member 6 when assembled therewith, the inner end of the hub-member 7 being equipped with an angle-shaped 85 flange 10, the portion 11 of which extends substantially parallel with the flange 9 and is spaced therefrom, as shown, and the annular portion 12 of which overlaps the periphery of the flange 9, thus forming with 90 the flanged portion 9 of the inner hub-member an annular housing about the latter.

The portion 11 of the outer hub-member 7 is provided, preferably at equal intervals, with a series of pins 13 which extend laterally from the flange 11, in a direction generally lengthwise of the hub, and into sockets 14 provided in thickened portions 15 of the flange 9 at its inner side. The pins 13 are rigidly held in position on the flange 11 by 100 means of the flanges 16 and 17 interlocking with the inner and outer faces of the flange 11, these pins and the sockets 14, in the particular illustrated embodiment of the invention, being of such form and size that the 105 inner ends of the pins 13 will snugly fit in the sockets 14 when the inner and outer hub-members are assembled to the position shown in Fig. 1. It may be here stated that according to the preferred illustrated embodiment of the invention the pins 13 operate 110 to hold the inner and outer hub-members to-

H. YATES.
 ANTICREEP DEVICE OR ANCHOR FOR RAILWAY RAILS.
 APPLICATION FILED FEB. 17, 1920.
1,353,206. **Patented Sept. 21, 1920.**
 2 SHEETS—SHEET 2.

*Inventor.
 Hubert Yates.

 Attorney*

UNITED STATES PATENT OFFICE.

HUBERT YATES, OF CHEAM, ENGLAND.

ANTICREEP DEVICE OR ANCHOR FOR RAILWAY-RAILS.

1,353,206.

Specification of Letters Patent. Patented Sept. 21, 1920.

Application filed February 17, 1920. Serial No. 359,338.

To all whom it may concern:

Be it known that I, HUBERT YATES, a subject of the King of Great Britain and Ireland, residing at Cheam, in the county of Surrey, England, whose post-office address is Coombe Cottage, Devon Road, Cheam, in the county of Surrey, England, have invented certain new and useful Improvements in Anticreep Devices or Anchors for Railway-Rails; and I do hereby declare the following to be a full, clear, and exact description of the invention, such as will enable others skilled in the art to which it appertains to make and use the same.

This invention relates to anti-creep devices or rail anchors for railway rails, and has for its principal object to provide a rail anchor which can be produced cheaply and which shall be easy to apply or install and at the same time highly effective in action.

The invention further consists in the anti-creep device or rail anchor comprising the wedge member and clip adapted to be applied to the foot of the rail substantially as hereinafter described with reference to and as shown in the accompanying drawings in which:—

Figure 1 is a side elevation of a portion of a flat bottomed rail with an anti-creep device or rail anchor according to this invention applied to the foot of the rail.

Fig. 2 is a plan view of Fig. 1.

Fig. 3 is a transverse section on the line A, B Figs. 1 and 2.

Fig. 4 is a plan view of the clip or yoke which embraces the foot of the rail.

These figures illustrate the rail anchor applied to a flat bottomed rail.

Figs. 5, 6, 7 and 8 are corresponding views to Figs. 1 to 4 but show the rail anchor applied to a double headed rail, Fig. 7 being a transverse section taken on the line C—D Figs. 5 and 6.

Like reference numbers indicate corresponding parts in the several figures of the drawings.

1 shows a portion of a flat bottomed rail, 2 is the clip or yoke adapted to embrace the foot of the rail, and 3 is the taper key or wedge adapted to be embraced by the clip or yoke 2 and to bear at its inner side against the foot 4 of the rail as shown, 5 being the downwardly projecting part formed on the taper key or wedge 3 and adapted to abut against the sleeper as in the case of pre-

viously proposed rail anchors or anti-creep devices. The clip or yoke 2, consists of a stamping made of steel plate, the said clip comprising the upstanding portions 6 and 7 at opposite ends with the inwardly projecting portions or fingers 6^a and 7^a respectively, the projection or finger 6^a bearing, with its lower edge or face at right angles to the web 1^a of the rail, on the top of the key or wedge 3 as shown in Figs. 2 and 3. As shown in Fig. 3 the wedge or key 3 is recessed or undercut along its inner side which abuts and presses laterally against the foot 4 of the rail, the overhanging portion 3^a of the wedge or key bearing on the top side of the foot 4. As shown in Figs. 2 and 3 the downwardly projecting part 5 of the wedge 3 projects a considerable distance on either side of the body of the wedge so as to provide an effective face or bearing surface to contact with the sleeper. Further, as shown in Fig. 3, the underside or face of the overhanging portion 3^a of the wedge 3 slopes upwardly toward the center or web 1^a of the rail to conform to the top face of the foot 4 of the rail. Also Fig. 3 shows a clearance, indicated at 9, provided between the outside of the wedge 3 adjacent the top thereof and the upstanding portion 6 of the clip 2, this clearance being provided by forming a recess in the body of the wedge throughout its length.

The anti-creep device or rail anchor illustrated in Figs. 5—8 inclusive is identically the same as that above described with reference to Figs. 1—4 inclusive with the exception that the depth or height of the clip or yoke 2 and of the body of the wedge 3 is made suitable for application to a bull-headed or double headed rail.

As shown in Figs. 2, 4, 6 and 8 the inwardly projecting portion 7^a of the clip 6 is set or bent toward the sleeper or in the direction of the creep.

As clearly shown in Figs. 3 and 7 the underside of the body of the key or wedge 3 slopes upwardly toward the rail so that the body of the wedge member 3 is thicker or deeper at its outer side than at its inner side, whereby the aforesaid clearance between the bottom of the wedge or key 3 and the transverse portion of the clip 2 is provided for the purpose of enabling the part 3^a of the fastening wedge member to bear hard on the rail irrespective of roughness and irreg-

ularity of the surfaces which are placed in contact with each other.

For applying the clip 2 to the foot of the rail the inward projection of finger 6^a at one end of the clip is first hooked over the foot 4 of the rail and the other end of the clip, with upstanding projections 7 and finger 7^a is then raised and moved laterally or transversely of the rail into the position 10 in which the projection or finger 7^a rests on the foot of the rail as shown in Figs. 2 and 7; the wedge or key 3 is now applied to the foot of the rail, with its overhanging part 3^a resting thereon, after which the clip 15 2 is moved in the direction of the length of the rail into position to embrace or engage the wedge 3 and is tightened thereon by blows by a hammer or other suitable implement applied alternately at opposite ends 20 of the clip 2. The clip 2 is relatively thin in proportion to its breadth, to accord the necessary strength together with narrow bearing surfaces which do not require to be fitted to the rail or to the fastening wedge 25 member. The clip is formed of resilient metal so that when it is hammered onto the rail and the wedge member its material is placed in tension so that the clip is partially held in place by its own resilience.

30 When the clips are constructed in this manner they can be stamped out in large quantities at a small cost, and they are all interchangeable with each other.

In certain cases, for instance where metal 35 sleepers are employed, the face of the above mentioned downward projection or flange at the end of the wedge may be suitably formed, for instance inclined, so as to insure an effective bearing of the face against 40 the sleeper or its fastening.

Further in certain cases the above mentioned downward projection 5 at the wider end of the wedge member 3 may be omitted; for instance it may be omitted in the case 45 of steel sleepers with steel keys or wedges for securing the rail to the sleeper, in which case the end of the body of the wedge member 3, when in position on the rail, would abut against the adjacent end of the afore- 50 said steel key or wedge securing the rail to the sleeper.

The hereinbefore mentioned upwardly sloping bottom or lower face of the body of the wedge member 3 is indicated at 10 at 55 Figs. 3 and 7.

With an anti-creep device or rail anchor

as hereinbefore described, on conditions arising that tend to cause the rail to move or creep toward the sleeper, *i. e.* in the direction of the arrow Figs. 1 and 5, owing to the wider end or the depending part 5 of the wedge member 3 being pressed tightly against the sleeper any such movement or creep will be prevented, the wedge member 3 and clip 2 being, by the increased pressure 60 put on the wedge, clamped or forced more tightly together and to the foot of the rail. In the case of a metal sleeper and a metal key securing the rail to the sleeper, the wider end of the body of the wedge member 70 3 (the depending portion or plate 5 being in this case omitted) abutting or pressing hard against the adjacent end of the key securing the rail to the sleeper, not only tightens the member 3 and clip 2 together 75 and on the foot of the rail if creep tends to take place, but also tends to tighten the key securing the rail to the sleeper.

What I claim as my invention and desire to secure by Letters Patent is:—

1. An anti-creep device for a rail, comprising a non-slidable fastening wedge member adapted to bear against one side portion of a rail, and a clip having hook-shaped end portions for engaging with the rail and the wedge member, said wedge member having a recess extending downwardly from the top of its outer side whereby a clearance space is provided between the upper portion of the wedge member and the adjacent 90 upstanding portion of the clip.

2. An anti-creep device for a rail, comprising a non-slidable fastening wedge member substantially rectangular in cross-section and deeper at its outer side than at 95 its inner side which bears against the rail, said wedge member having a projecting lip at the top of its inner side which overlaps the adjacent part of the rail, and a clip having hook-shaped end portions for engaging 100 with the rail and the wedge member, a clearance space being formed between the inner side portion of the wedge member and the upper part of the clip whereby the bearing of the said lip on the rail is assured.

In testimony whereof I have affixed my signature, in the presence of two witnesses.

HUBERT YATES.

Witnesses:
